(57) **CLAIM**

The ornamental design for a multi-sensor device, as shown and described.

DESCRIPTION

FIG. 1 is a front perspective view of a multi-sensor device in accordance with a first embodiment.

FIG. 2 is a bottom-side view of a multi-sensor device in accordance with a first embodiment.

FIG. 3 is a top-side view of a multi-sensor device in accordance with a first embodiment.

FIG. 4 is a left-side view of a multi-sensor device in accordance with a first embodiment.

FIG. 5 is a right-side view of a multi-sensor device in accordance with a first embodiment.

FIG. 6 is a front view of a multi-sensor device in accordance with a first embodiment.

FIG. 7 is a back view of a multi-sensor device in accordance with a first embodiment.

FIG. 8 is a front perspective view of a multi-sensor device in accordance with a second embodiment.

FIG. 9 is a bottom-side view of a multi-sensor device in accordance with a second embodiment.

FIG. 10 is a top-side view of a multi-sensor device in accordance with a second embodiment.

FIG. 11 is a left-side view of a multi-sensor device in accordance with a second embodiment.

FIG. 12 is a right-side view of a multi-sensor device in accordance with a second embodiment.

FIG. 13 is a front view of a multi-sensor device in accordance with a second embodiment.

FIG. 14 is a back view of a multi-sensor device in accordance with a second embodiment.

FIG. 15 is a front perspective view of a multi-sensor device in accordance with a third embodiment.

FIG. 16 is a bottom-side view of a multi-sensor device in accordance with a third embodiment.

FIG. 17 is a top-side view of a multi-sensor device in accordance with a third embodiment.

FIG. 18 is a left-side view of a multi-sensor device in accordance with a third embodiment.

FIG. 19 is a right-side view of a multi-sensor device in accordance with a third embodiment.

FIG. 20 is a front view of a multi-sensor device in accordance with a third embodiment; and,

FIG. 21 is a back view of a multi-sensor device in accordance with a third embodiment.

Subject matter shown in broken lines is environmental and forms no part of the claimed design. However, the Applicant reserves the right to claim any combination or subset of
